UNITED STATES PATENT OFFICE.

HARRY L. BISBING, OF CLERMONT, IOWA.

END-GATE.

1,110,740.

Specification of Letters Patent. Patented Sept. 15, 1914.

Application filed June 4, 1913. Serial No. 771,655.

To all whom it may concern:

Be it known that I, HARRY L. BISBING, citizen of the United States, residing at Clermont, in the county of Fayette and State of Iowa, have invented certain new and useful Improvements in End-Gates, of which the following is a specification.

This invention relates to improvements in the end gates of wagon bodies, and has for one of its objects to provide a simply constructed device which may be readily applied without detaching any of the parts.

Another object of the invention is to provide a simply constructed device which may be instantly secured in position, and which may be likewise utilized to draw the sides of the wagon body toward each other and to effectually prevent separation under the lateral strains of the load.

Another object of the invention is to provide a simply constructed device which may be readily adapted to wagon bodies of different sizes without material structural change either in the wagon body or in the attachment.

With these and other objects in view the invention consists in certain novel features of construction as hereinafter shown and described and then specifically pointed out in the claims, and in the drawings illustrative of the preferred embodiment of the invention.

Figure 1 is an elevation of the rear end of a wagon body including the end gate with the improvement applied. Fig. 2 is a plan view of the same. Fig. 3 is a perspective view from the rear of the casing which supports the rotative strain applying member. Fig. 4 is a perspective view from the front of the casing which supports the rotative strain applying member. Fig. 5 is a detached perspective view of the rotative strain applying member.

Corresponding and like parts are referred to in the following description and indicated in all the views of the drawings by the same reference characters.

The improved device may be applied to end gates of different sizes, and in the drawings the side members of the body are represented conventionally at 10-11 and the bottom at 12. The sides 10-11 are provided with spaced cleats 13 between which the terminals of the end gate 14 are slidably

engaged, these parts being of the usual construction. The end gate 14 is provided with cleats 15, preferably of metal L bars, with one web bearing upon the end gate and secured in position by screws or other fastening devices 16 and with the other web extending rearwardly and at right angles to the rear face of the end gate. The outstanding webs of the cleats 15 are perforated to receive the tie rods 17-18. Extending through the outer cleats 13 and likewise through the contiguous portion of the side members 10-11, are eye bolts 19, each bolt being provided with an outer clamp nut 20 bearing against the outer face of the member 10-11, and with an inner nut 21 bearing against the inner surface of the cleats 13. By this means the eye bolts may be adjusted longitudinally as will be obvious.

The rods 17-18 are provided at their outer ends with hooks 22-23 engaging in the eye bolts 19 as shown. Attached to the rear face of the end gate 14 intermediate the cleats 15 is a casing 24 having a relatively large central opening and securing ears whereby the casing may be secured by screws or other suitable devices to the end gate. The opening in the outer wall of the casing being smaller than the casing, a stop flange 25 is produced, as shown. The casing 24 is hollow and adapted to receive a disk member 27 provided with a projection 28 engaging through the opening and against the stop flange 25. The disk 27 is provided with transverse apertures 29-30 spaced at equal intervals from its center. The casing 24 is provided with a recess 31 in its inner face at one side through which one of the rods, for instance the rod 18, extends at its inner end and is out-turned at 32 to pass through the aperture 30, while the other rod 17 is in-turned at 33 to pass in through the aperture 29. The rod 18 thus operates between the disk 27 and the end gate 14, and likewise internally of the casing 24, while the rod 17 operates externally of the casing. The rods 17-18 are likewise provided with intermediate offsets so that the portions extending through the cleats 15-16 are spaced away from the end gate 14 the same distance as where they pass through the cleats.

Extending from the projection 28 of the disk 27 is an operating arm 34, preferably

somewhat resilient, and adapted to engage between projections 36—37 upon the lower ear of the casing. The arm 34 extends at right angles to the normal position of the rods 17—18 and thus locks the rods in position when in this position, as shown in Figs. 1 and 2. The arm 34 is so located that when in its downward position and in engagement between projections 36—37 the aperture 29 will be nearest to the side member 11, while the aperture 30 will be nearest to the side member 10. The rods 17—18 will thus be maintained substantially in longitudinal alignment and strain will be applied to draw the sides 11—12 toward each other when the lever arm 34 is moved into its locked position, and then when the arm 34 is released and turned into a horizontal position, or into an upward position, the rods 17—18 will be fully released so that the end gate together with the rods and the rod operating mechanism may be removed bodily and without detaching any of the parts. When the improved device is to be applied the lever arm 34 is disposed in its upward position to release the strain upon the rods 17—18 and the end gate disposed between the guide cleats 13. The terminals 22—23 of the rods are then disposed in the eyes of the bolts 19 and the lever arm 34 moved into its downward position until it engages between the projections 36—37. This movement, it will be obvious, applies a pulling strain upon the rods 17—18 and likewise draws the side members 10—11 firmly toward each other and locks them in position, and by adjusting the nuts 20—21 upon the eye bolts this strain can be increased or decreased as required. The improved device is simple in construction, can be inexpensively manufactured and applied. The device reduces materially the labor and time required to handle the end gate, as the movements by which the gate is secured or released are substantially instantaneous. The improved device also enables the sides 10—11 to be drawn toward each other, and thus obviates any tendency of the sides to draw apart or to be distended under the strains of the load within the body.

Having thus described the invention, what is claimed as new is:

1. A device of the class described comprising a casing adapted to be attached to an end gate and having an opening in its front face surrounded by a stop flange, a member mounted for rotation in said casing and against said stop flange, an arm extending from said rotative member and through the opening of the casing, rods connected to said rotative member at opposite sides thereof and adapted to be detachably coupled to the opposite sides of a wagon body, and a holding member engaging said arm. 65

2. An end gate operator comprising an annular casing adapted to be attached to an end gate and having a marginal recess in one side and an annular stop flange, a member mounted for rotation in said casing and bearing against said stop flange, an arm extending from said rotative member and externally of said casing, a rod connected to said rotative member externally thereof at one side of its center and adapted to be detachably coupled to a wagon body at one side thereof, another rod extending through the recess of the annular casing and connected to the rotative member internally thereof and at the opposite side of its center and adapted to be detachably coupled to a wagon body at the opposite side thereof. 75

3. A device of the class described comprising a casing adapted to be attached to an end gate and having an opening in its front face surrounded by a stop flange and with depending stops spaced apart, a member mounted for rotation in said casing and against said stop flange, an arm extending from said rotative member and through the opening in the casing and adapted when in one position to engage between said spaced stops, and rods connected to said rotative member at opposite sides thereof and adapted to be detachably coupled to the opposite sides of a wagon body. 95

In testimony whereof I affix my signature in presence of two witnesses.

HARRY L. BISBING. [L. S.]
